UNITED STATES PATENT OFFICE.

JOHN BOUCHARD, OF CHICAGO, ILLINOIS, ASSIGNOR OF ONE-HALF TO
MICHAEL CUHADY, OF SAME PLACE.

SWITCH FOR OVERHEAD TRACKS.

SPECIFICATION forming part of Letters Patent No. 399,008, dated March 5, 1889.

Application filed March 31, 1888. Serial No. 269,166. (No model.)

To all whom it may concern:

Be it known that I, JOHN BOUCHARD, a citizen of the United States, residing at Chicago, in the county of Cook and State of Illinois, have invented a certain new and useful Improvement in Switches for Butchers' Tracks, which is fully set forth in the following specification, reference being had to the accompanying drawings, in which—

10 Figure 1 represents an elevation of a structure embodying my invention; Fig. 2, a plan view of the same; Fig. 3, a plan section taken on the line 1 1 of Fig. 1, and Fig. 4 an end view.

15 Like letters refer to like parts in all the figures of the drawings.

My invention relates to switches for butchers' tracks, and is in the nature of an improvement upon the construction set forth in 20 an application filed by me October 21, 1887, Serial No. 253,039.

25 I will now proceed to describe a construction in which my invention is practically carried out in one form, and will then particularly point out in the claims those features which I deem to be new and desire to protect by Letters Patent.

30 In the drawings; A represents the ceiling, overhead beam, or other part from which the track is suspended, and B the hangers attached thereto and supporting the track.

35 C represents the single line of track, which I will term the "main line," and C' and C² the branch lines to which the main line is to be connected. The general construction of these tracks and of the trucks which travel thereon is well known and needs no extended description here, it being only necessary to state that they may be of any approved construction for the purpose.

40 D represents a switch-rail, which is adapted to swing horizontally in the arc of a circle, one end of said switch-rail remaining always in line with or opposite the end of the main line C, while its other end may by this swinging movement be brought in line with or opposite the end of either of the branch lines C' or C².

45 The switch-rail D may be connected to the main line C in the manner set forth in my prior application hereinbefore referred to;

but in practice I prefer a construction which I have devised for this purpose, and which is as follows: A hanger, B, is arranged at or near the end of the main line C, and is provided 55 with a horizontal shoe or sole plate, b, the switch-rail D being provided with a pivot-pin, d, by means of which it is pivoted to the said hanger. The hangers B, which support the ends of the branch lines C' and C², are also 60 provided with similar shoes or sole plates, b, and these plates are provided with upwardly-extending lugs b', which form stops to limit the motion of the switch-rail D and hold the same in proper position. Upon the switch- 65 rail D there is mounted at the side thereof a lug, D', having a slot, d', with which engages a pin, e, on an arm, E, attached to the lower end of a vertical rock-shaft, E'. This rock-shaft is mounted in suitable bearings in a 70 hanger, B, and is provided at its upper end with an arm, e'.

75 F indicates a lever connected to the arm e' at one end by means of a link, e², its other end being connected by means of a pivot-bolt, f, to a lever, F', pivoted on a plate, G, attached to an upright, G'. The levers F and F' form a pair of toggle-levers, which are operated by means of a hand-lever, H, which is pivoted on the pivot-bolt f, connecting the levers F and F'. The lever H passes down 80 loosely through a keeper, g, on the upright G', and is perforated at h to receive a pin, g', on the said upright, by means of which the said lever may be held either in a raised or a 85 lowered position. The lever F' is provided with a toe, f', which, when the lever H is lowered, strikes against the upright G and limits the downward motion thereof.

90 The operation of the device is as follows: When the parts are in the position shown in full lines in the drawings, the switch-rail D connects the main track C with the branch track C². When it is desired to connect the main track with the branch C', it is only necessary to move the lever H outward, so as to disengage it from the pin g', and then pull the said lever downward, when the action of the toggle-levers F and F' will, through the medium of the arm e', rotate the rock-shaft E' 95 and cause the arm E thereof to swing the switch-rail D over into the position shown in 100

dotted lines in Fig. 3 of the drawings, in which position it connects the main line with the branch line C'. The plates b form supports for the switch-rail to prevent any sagging thereof, and the stops b' thereon limit the motion of the switch-rail, so as to arrest the same when in proper position. The toe f' of the lever F' also acts as a stop and prevents the toggle-levers from passing below a horizontal line, and thereby returning the switch-rail to its original position. In practice the weight of the lever H is sufficient when the said lever is disengaged from the pin g' to throw the switch, so that when the lever H is freed from the pin g' it will always hold the switch-rail in line with the branch line C', which may be regarded from its position as a continuation of the main line C'.

It will be observed that the switch-rail, instead of being pivoted to the end of the main rail, as is customary, is pivoted to an independent hanger. By this construction I am enabled to obtain a pivot which in no way decreases the strength of the track at this point, since it is not necessary to halve the main and switch rails to pivot them to each other nor to employ a hinged joint to connect the two, which joint would necessarily be weaker than the rest of the rails. Moreover, by providing a separate hanger at this point and pivoting the switch thereto instead of to the main rail I am enabled to prevent any sagging of the track at the point where the ends of the main and switch rails meet, and thus obviate a weakness which frequently, if not always, develops at this point when the switch-rail is pivoted immediately to the end of the main rail.

It is obvious that various modifications in the details of construction and arrangement of parts may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. The combination, with the main and branch lines, of the horizontally - swinging switch-rail, a vertical rock-shaft having one arm connected to said switch-rail, and a second arm by which it is operated, a pair of toggle-levers connected to said second arm and to a fixed support, and an operating-lever connected to said toggle-levers, substantially as and for the purposes specified. 55

2. The combination, with the main and branch lines, of the horizontally - swinging pivoted switch-rail, the rock-shaft E', having arm E connected thereto, and arm e', the toggle-levers F and F', the former connected to the arm e' by means of link e², and the latter pivoted to a fixed support, the operating-lever H, pivoted to the toggle - levers, and means for locking said operating-lever, substantially as and for the purposes specified. 60

3. The combination, with the swinging switch-rail and the rock-shaft E', for operating the same, of the toggle-levers F and F', the former connected to said rock-shaft and the latter pivoted to a suitable fixed support and provided with a toe, f', to limit its downward motion, substantially as and for the purposes specified. 70

4. The combination, with the swinging switch-rail, its rock-shaft, and the toggle-levers for operating the same, of the support G, having keeper g and pin g', and the operating-lever H, pivoted to the toggle - levers, passing through the keeper, and apertured at h to receive the pin g', substantially as and for the purposes specified. 75 80

JOHN BOUCHARD.
